DESIGN FOR A SCARF OR SIMILAR ARTICLE

Marcel Vertes, New York, N. Y.

Application October 19, 1942, Serial No. 108,564

Term of patent 3½ years

To all whom it may concern:

Be it known that I, Marcel Vertes, a citizen of France, residing in New York city, county of New York, and State of New York, have invented a new, original, and ornamental Design for a Scarf or Similar Article, of which the following is a specification, reference being had to the accompanying drawing, forming part thereof.

The figure on the drawing is a plan view of a scarf or similar article showing my new design.

I claim:

The ornamental design for a scarf or similar article, substantially as shown.

MARCEL VERTES.
